STEEL REINFORCED FIBER CONTAINER

James A. Eden, Jr., Springfield, Mass., assignor
to General Container Corporation, Boston,
Mass., a corporation of Massachusetts

Application August 11, 1933, Serial No. 684,700

7 Claims. (Cl. 229—67)

My invention relates to a container or barrel having a steel or metal structure integrally united with a fibrous surface material to which paints or coating materials may be applied and to which they will permanently adhere.

Barrels and similar containers made of sheet steel or other metal have advantages in strength and toughness inherent in the characteristics of the metals from which they are formed. But, they do not provide surfaces that can be penetrated by paints, resins, waxes, etc., sufficiently to provide a firm anchorage for such materials. As a result the coating of the surfaces, particularly the inner surface of metal containers is apt to be imperfect or to lack permanence, so that the contents of the container may reach the surface of the metal itself. Other materials to which waxes, resins and other coating materials adhere with great tenacity and permanency, however, lack the strength and toughness provided by metallic structures.

Metal containers also induct heat rapidly which is a dis-advantage when chilled liquids are to be shipped therein.

An object of my invention is to provide a barrel or other container having a strength and resistance to stresses approaching or equaling that of a bilged metal barrel and having integrally formed therewith a structure of fibrous or other nature to which paints, resins, waxes and other coating materials readily and permanently adhere.

Further objects of my invention are to provide a barrel or container of metal staves and a fibrous material united in such manner that the fibrous structure is an integral structure, integrally united to the metal staves structure and inseparable therefrom without destroying the integrity of the fibrous structure. Also provides a metal container insulated against the passage of heat.

Other objects of the invention will appear more specifically from the following description.

The various features of the invention are illustrated by way of example in the accompanying drawings in which Fig. 1 is a longitudinal sectional view, and Fig. 2 a cross-sectional view, of a barrel embodying a preferred form of the invention; Fig. 3 shows a flat stave blank as it is sheared from a sheet of metal; Figs. 4, 5 and 6 are respectively a side view, an edge view and an end view of a stave rolled and bilged to the shape required in forming a barrel or bilge container; Fig. 7 is a view showing a paper strip to be wrapped into a fibrous structure in forming a barrel or container.

In forming a container in accordance with the present invention, a strip of paper 10 is wrapped on the surface of a mandrel which is of a shape and size corresponding to the inner surface of the container to be formed. The strip of paper 10 may be corrugated with the corrugations 11 extending transversely to the length of the strip and preferably somewhat larger in the median part of the strip. A number of layers of the paper wrapping are thus built up on the outer surface of the mandrel, the layers being cemented together by a suitable cementing material to form an inner fibrous wall 12. For example 12 layers of paper having a thickness of 0.03 inches may be wound on a mandrel, each layer being 15 impregnated or coated with a rubber latex or dispersion, water glass, glue, asphalt, pitch or other material, so that an integrally cemented fibrous wall of about 36/100ths of an inch is formed. It will be understood that the number of layers and 20 the thickness of wall may be varied for different sizes of containers for different requirements.

Metal staves 13 are then placed on the outer surface of the wall 12, the width and number of the staves being such that their side edges meet 25 at each end, but separate progressively from each end toward the mid-section of the barrel owing to the bilge shape. Spaces 14 are, therefore, formed between the staves where the latter separate except at each end of the barrel or container.

An outer wall 15 of fibrous structure is then formed on the outer surface of the staves by wrapping more paper strip 10 of fibrous material from the strip 10 on to the outer surface of the staves, 35 the layers being cemented similarly to those of the inner wall 12 so as to form an integral structure. The outer fibrous wall 15 may be formed of any desired number of layers of wrappings to provide the required thickness of material. It 40 may, for example, be formed of 12 wrappings of the paper strip to equal the thickness of the inner fibrous wall structure. The thickness of the metal staves is so proportioned to the size of the container and to the spaces 14, that as the paper 45 is wrapped on the outer surface of the staves it will contact with the paper of the inner wall structure through these spaces thereby integrally joining the inner and outer fibrous wall structures into a single integral structure that embeds the 50 staves 13. The fibrous walls cannot, therefore, be separated from the staves without destroying their integral structure.

In a typical embodiment of the invention staves having a thickness of 0.03 inches and a width of 55

4.7 inches was found suitable for a container requiring 10 of such staves to form the desired diameter.

When the reenforced fibrous structure has thus been formed, the mandrel is collapsed sufficiently to enable it to be withdrawn through one end of the barrel structure. The construction and use of the mandrel is not described as it is a known piece of apparatus. When the mandrel has been withdrawn, heads 16 and 17 are secured to the ends of the barrel structures. These heads are formed of a metal having a lining 18 of impregnated paper or other suitable material. The outer peripheral edges of the heads are shaped to form annular recesses 19 into which the opposite ends of the barrel stave structure may be inserted. The head is then secured to the staves 13 by means of rivets 20 passing through the staves and the peripheral walls of the recesses 19 and drawing the walls of the recesses tightly against the fibrous structure enclosing the staves. Two rivets are preferably used for each stave symmetrically spaced near the side edges as shown in Fig. 1. Bung openings 21 and 22 may then be formed in the barrels and head respectively. Hoops 23 and 24 may also be placed on the outer surface of the barrel, if desired, for greater strength.

The bilged metal stave structure may be formed in any suitable manner to provide the bilge form and the longitudinally extending openings 14. As illustrated, in Figs. 3 to 6 inclusive, blanks 25 of proportionate width and length are cut or stamped from sheet metal and then curved and bent or stamped to give them the required stave shape. That is, the blank is curved transversely as indicated at 26 in Fig. 6 and curved longitudinally as indicated at 27 in Fig. 5. When staves thus curved and assembled in a circular or cylindrical fashion with the side edges in abutment near their ends, the edges of adjacent staves diverge from point of contact toward the center of the stave as indicated diagrammatically in Fig. 4.

The outer surface of the barrel may be protected and strengthened by means of sheet metal surface plates 28 and 29 placed between the hoops 23 and 24, and the outer edges of the heads 16 and 17 respectively. This covering sheet conforms in shape to that of the surface of the container and fits the latter. They serve to protect the outer surface of fibrous material from abrasion as well as to strengthen the structure. Their use, however, is optional.

Through the above invention, a barrel or container is formed which has shaped staves having a rigidity, strength and toughness inherent in curved or rounded bilge sheet metal, and, therefore, capable of withstanding the shocks and stresses inherent in dropping the barrel or container on its chimes as is customary in handling barrels. The fibrous structure formed integrally through the openings 14 and covering both sides of the staves provides a surface to which coating materials such as paraffin, wax or pitch, readily and permanently adhere, while at the same time it forms an integral non-separable structure with the staves 13. While the container has the strength of a metallic structure, it has less heat conductivity and, therefore, chilled liquids may be exposed to warm temperature for a considerable time without undesirable changes in the temperature.

Various modifications may be made by those

skilled in the art without departing from the following claims.

What I claim is:—

1. A container having bilged metal staves in barrel formation, the side edges of said staves contacting at their ends and separating in the intermediate bilged portion and a fibrous structure covering the inner and outer faces of said staves and uniting to an integral structure through the spaces between the separated intermediate edges 10 of said staves.

2. A container having metal staves in barrel formation, the side edges of said staves contacting at their ends and separating intermediate said ends, a fibrous structure on the inner and outer faces of said staves and uniting to an integral structure through the spaces between the separated intermediate edges of said staves, heads having peripheral recesses receiving the ends of said staves and means securing the stave ends in 20 said recesses.

3. A container having metal staves in barrel formation, the side edges of said staves contacting at their ends and separating intermediate said ends, a paper wrapping on the inner and outer 25 faces of said staves and uniting to an integral structure through the spaces between the separated intermediate edges of said staves, heads having peripheral recesses receiving the ends of said staves and means securing the stave ends in 30 said recesses.

4. A container having metal staves in barrel formation, the side edges of said staves contacting at their ends and separating intermediate said ends, a paper wrapping impregnated with an 35 adhesive material on the inner and outer faces of said staves and uniting to an integral structure through the spaces between the separated intermediate edges of said staves, heads having peripheral recesses receiving the ends of said 40 staves and means securing the stave ends in said recesses.

5. A bilged container having a bilged sheet metal structure, the ends thereof being peripherally continuous and having widening spaces from 45 near the ends to the central part of the container between stave areas, and fibrous wrappings on the inner and outer faces of said metal structure, said wrappings being cemented together through said spaces.

6. A container having bilged metal staves in barrel formation, the side edges of said staves contacting at their ends and separating in the intermediate bilged portion and paper wrappings covering the inner and outer faces of said staves 55 and uniting to an integral structure through the spaces between the separated intermediate edges of said staves.

7. A container having metal staves in barrel formation, the side edges of said staves contacting at their ends and separating intermediate said ends, a fibrous structure on the inner and outer faces of said staves and uniting to an integral structure through the spaces between the separated intermediate edges of said staves, heads 65 having peripheral recesses receiving the ends of said staves and means securing the stave ends in said recesses, hoops on the outer surface of said fibrous structure and protecting metal plates extending between said hoops and the heads of said 70 container.

JAMES A. EDEN, JR.
